(57) CLAIM

We claim the ornamental design for a basketball, as shown and described.

DESCRIPTION

The patent file contains at least one drawing executed in color. Copies of this patent with color drawing(s) will be provided by the Patent and Trademark Office upon request and payment of the necessary fee.

FIG. 1 is a front view of the basketball showing our new design;

FIG. 2 is a left side view of FIG. 1; and,

FIG. 3 is a right side view of FIG. 1.

The broken (dash-dot-dash) lines that define the boundaries of the claim form no part thereof.

1 Claim, 3 Drawing Sheets
(3 of 3 Drawing Sheet(s) Filed in Color)
